UNITED STATES PATENT OFFICE.

GEORGE P. HERTHEL, JR., OF ST. LOUIS, MISSOURI.

IMPROVED TRUSS-BRIDGE.

Specification forming part of Letters Patent No. 86,227, dated January 26, 1869.

To all whom it may concern:

Be it known that I, GEORGE P. HERTHEL, Jr., of the city of St. Louis, in the county of St. Louis and State of Missouri, have made certain new and useful Improvements in Truss-Bridges; and I do hereby declare that the following is a full and clear description thereof, reference being had to the accompanying drawings, and to the letters of reference marked thereon.

It is well known that the braces of a truss-bridge are subject to a maximum strain only when the transient load carried by the bridge occupies a certain position relatively to said braces; but, as the braces must be constructed of a strength of material to resist the maximum strain, it is apparent that the braces during their action, under any but the position of load causing a maximum strain, have a surplus of strength. The nature of this invention is now to employ said surplus of strength to strengthen certain other parts of the truss, and thus to permit and make an economy of material in such other parts. These are usually the upper and sometimes the lower chords of the truss.

It will hereafter be seen that in the application of the braces for trussing upper or lower chords a series of what may be called "secondary trusses" is formed; and this gives rise to certain new features of detail construction, which thus are resultants from the nature of this invention, as aforesaid.

It is well known that it is usual to construct trusses of bridges and similar structures with certain parts adjustable, thus enabling an operator to adjust such parts to any inequalities of construction or action, and when such structures, after use, become permanently deflected below their original outline, or "sagged," they are drawn up, or "cambered," at the points of adjustability. It seems apparent that in the repeated adjustments thus made, the parts so drawn up or readjusted should be subjected to greater strain than originally intended, and thus a weakening of the structure may arise. In order to counteract such effects, and generally to form, after adjustment, a stronger and safer structure, the nature of this invention is in such an arrangement for readjusting the vertical members, posts, or struts of a truss that thereby

the truss height between the centers of chords will be increased, thereby increasing the resistance of the truss to strains, and counterbalancing, in whole or part, the undue strain on any individual member of the truss caused in the process of adjustment.

To enable those skilled herein to make and use my said improvements, I will now more fully describe the same, referring to—

Figure 1 as a general side elevation; to Fig. 2 as an end elevation; to Fig. 3 as an enlarged detail elevation; to Figs. 4 and 5 as detail section and elevation, respectively showing one form of connecting posts with the upper chords; and to Figs. 6 and 7 as detail section and elevation, showing a second form of connecting posts and upper chords.

The features heretofore indicated as peculiarly in the nature of this invention are in no wise limited to the special details now to be described, and the forms as indicated in the figures are intended as representative of one form of the application of the said features.

I construct the upper chord of the chord-pieces A, which are usually cast-iron pipes, abutting against king-bolts a.

The posts or struts B abut also against said king-bolts, and the braces C attach thereto by any usual form of joint.

The queen-bolts d pass between the bands D of the lower chord, generally as indicated in Figs. 1, 2, and 3.

To said queen-bolts the braces C again connect, and the struts B abut thereagainst, similarly as with the king-bolt a.

The braces cross at the point e, and a tie-bolt, e', passes through the same, thus connecting both main and counter braces.

Upon said cross-bolt e', I arrange a sleeve, e", which forms the abutment for the secondary post or strut b, and at the top this post connects, by a king-bolt, a', with the upper chord-piece, A, similarly as at the main-post joint.

By this construction the length of the upper chord-pieces between main posts B has been halved, and thus a great length of panel may be used, and the advantages following from a moderate length of chord-pieces A still retained.

Moreover, as every king-bolt is usually the

point for the arrangement of floor-beams E, it will be seen that the number of supports for the roadway of the bridge is largely increased.

The floor-beams E, I arrange upon the saddle-plate e, which sits upon the bolts a a', as indicated in the detail figures.

It is plain that the effect of a load upon the strut b, and herefrom upon the braces of any panel, is exercised only when that panel is subjected to load; and as it is true that the braces of this panel are not then subjected to a maximum strain, it is apparent that the surplus strength of the braces at the time the panel acts under a load is fairly economized.

Similarly, in case the load rests more immediately upon the lower chord, I arrange a post-bolt, F, passing from the king-bolt a to a queen-bolt, d', placed in the lower chord and similarly joined to the latter, as were the main queen-bolts d, as indicated in Figs. 1 and 3.

Now, as the upper chord of a truss is subject to compression by the action of loads on the truss, it may be necessary to prevent the bolt a' and its connecting chord-pieces from rising. This I accomplish either by a post-bolt, F, extending fully to the lower chord, or extending only to the lower surface of the sleeve c' of the cross-bolt c.

In the latter case the upward strain upon such bolt F acts upon the lower parts of the braces, and therefrom upon the lower chords, D, and main posts B, and is further thence distributed.

The bolt F may be continued up to hold down the floor-beams E, as in Figs. 3 and 5.

A second method of preventing the upper chord from buckling up at the joint a' is by the strap-bolts f, which pass about a flange of the posts b, and either around the bolt a' or go up to secure the floor-beams E, as in Figs. 6 and 7. In this case a similar strap, f', holds the lower end of the post b to the sleeve c'.

In order to adjust or readjust the parts here

described, I arrange, at the top or bottom of the main posts B or secondary posts b, a series of key-plates, g. These are of horizontal surface where they connect with the post, but are inclined on their upper surfaces, where they rest against the connecting king or queen bolt or sleeve. A set of small bolts g' is used to draw said key-plates together and secure them. If, now, the nut of said bolts g' is drawn up, the key-plates will be drawn together, and thus the king and queen bolts forced apart, the said operation being equivalent to lengthening the posts B or b, and thus increasing the truss height. But as hereby the strength of the truss is materially increased, if the load upon the truss be constant, the received strain on each part will be correspondingly decreased, owing to said increased height of truss, and thus any overstrain caused in adjusting any part will be in a degree counterbalanced.

Having thus fully described my said invention, what I claim is—

1. Connecting the main and counter braces with a secondary post, b, and with an intermediate point of the upper chord, to increase the number of points of support for the roadway, and shorten the lengths of the chord-pieces A, substantially as set forth.

2. The arrangement of the rod F, connecting the upper and lower chords at the point of juncture of the main and counter braces and the secondary post b, substantially as set forth.

3. The arrangement of the straps f f' or the rod F with the posts b and the bolt a' or floor-beams E, substantially as set forth.

4. The wedge-plates g, constructed and arranged, in connection with the post b or B, substantially as set forth.
